UNITED STATES PATENT OFFICE.

JAMES A. WATSON, OF SILVER SPRING, MARYLAND.

OIL-PURIFYING APPARATUS FOR HYDROCARBON ENGINES.

Application filed April 13, 1925. Serial No. 22,791.

The present invention relates to oil-purifying apparatus of the type described in my Patent Number 1,359,453, dated November 16, 1920. In this type of apparatus the oil used for lubricating the pistons, main bearings and other moving parts of the engine is automatically withdrawn, while the engine is running, and passed through a refining device which withdraws the gasoline, water, and other volatile impurities, the purified oil being returned to the crank case or other place of storage to be reused for lubricating.

It is well known that the diluents of crank case oil, usually gasoline and water, leak into the crank case from the combustion chambers by passing around the pistons and down the cylinder walls. The object of the present invention is to intercept these diluents and convey them to the refining device without permitting them to mingle with the body of oil in the crank case, thus maintaining the latter in a purer condition.

One embodiment of the invention is illustrated in the accompanying drawing in which

Figure 1 is a diagrammatic view of a four-cylinder engine equipped with a refining apparatus embracing the present invention;

Figure 2 is an enlarged side view of the engine, partly broken away; and

Figure 3 is a cross-sectional view about on the line 3—3 of Figure 2.

The refining apparatus proper may, for the purposes of the present application, be the same as that illustrated in Figures 1 to 4 inclusive of the aforesaid Patent No. 1,359,453 and fully described in the specification of that patent. As illustrated in the drawing of the present application, 10 indicates the hydro-carbon engine, 11 the exhaust pipe, 12 the intake manifold, 13 the throttle valve, 14 the carburetor, and 14^a the crank case.

The oil which drains from the cylinders is conveyed by suitable channels to a special compartment or container in the crank case from which it goes directly to the refiner. It is thus prevented from mingling with the body of oil in the crank case until after it has passed through the refining apparatus. As illustrated in the drawing, each cylinder is provided at or near its lower end with an oil collecting groove 15, preferably in the form of a gutter adapted to contain a

small quantity of oil. From the grooves 15 the oil drains through tubes 16, horizontal pipe 17, and tube 18, into a well or compartment 19 in the lower part of the crank case 60 and also located preferably midway of the length of the crank case for a purpose to be presently explained.

From the lower part of the well the oil is drawn up through the pipe 20 to the refiner A, which may be of the type described in Patent, 1,359,453 or of any other approved type. The volatile impurities in the oil are sucked into the intake 12 through the pipe 21 and the purified oil returned to the crank 70 case through the pipe 22.

The well or compartment 19 has its upper end above the normal level of the oil in the crank case and its lower end is preferably provided with a discharge opening and plug 75 23 to permit of drawing off solid matter which may collect in it. There is also preferably a small opening 24 in the lower part of the well which affords a restricted communication between the well and the main 80 oil reservoir 25 of the crank case. When the engine is running with the throttle nearly closed the vacuum in refiner A is greatest and more oil passes through it than when the throttle is open. It may happen that when the throttle is nearly closed more oil will pass through the refiner than is being drained from the cylinders and in such case oil from the crank case will pass to the well and the refiner through the opening 24. 85 Ordinarily, however the diluted oil in the well will not mix materially with oil in the crank case. The opening 24 may be omitted or plugged if desired.

This invention is particularly desirable 95 in multi-cylinder automobile engines and when embodied in such engines the well 19 should preferably be located, as shown, midway of the engine, where the oil level in the crank case is fairly uniform whether the automobile is going up or down grade or horizontal.

It will be noted that the invention may be embodied in simple and inexpensive form and its use will greatly facilitate maintaining the engine lubricating oil in pure and efficient condition. It will be obvious that the invention may be embodied in various forms in addition to that chosen for purposes of illustration, without, therefore, limiting myself to the particular apparatus shown and described.

I claim:

1. In an apparatus for purifying the oil in the lubricating system of a hydrocarbon engine, the combination with the engine having an oil supply reservoir, of a relatively small oil well separate from the reservoir, means for collecting the oil which drains from the engine cylinders and conveying the same to said well, a refining device, means for conveying the oil from the well to the refining device and means for returning the oil from the refining device to the reservoir, whereby oil draining from the cylinders is refined before its return to the reservoir.
2. In an apparatus for purifying the oil in the lubricating system of a hydrocarbon engine, the combination with the engine having an oil supply reservoir, of a relatively small oil well separate from the reservoir, means for collecting the oil which drains from the cylinders of the engine and conveying the same by gravity to said well, a refining device, means for conveying the oil from the well to the refining device and means for returning the oil from the refining device to the reservoir, whereby oil draining from the cylinders is refined before its return to the reservoir.
3. In an apparatus for purifying the oil in the lubricating system of a hydrocarbon engine, the combination with the engine having an oil supply reservoir, of a relatively small oil well separate from the reservoir, means for conveying the oil which drains from the engine cylinders to said well, a refining device, means for conveying the oil from the well to the refining device, and means for returning the oil from the refining device to the reservoir, said well being situated at substantially the same level as the oil supply reservoir and communicating therewith whereby the level of the oil in the well and the reservoir will be substantially the same.
4. In an apparatus for purifying the oil in the lubricating system of a hydrocarbon engine, the combination with an engine having a plurality of cylinders and having an oil supply reservoir below said cylinders, of a relatively small oil well separate from the reservoir and located midway of the engine, means for conveying the oil which drains from the engine cylinders to said well, a refining device, means for conveying the oil from the well to the refining device, and means for returning the oil from the refining device to the reservoir.
5. In an apparatus for purifying the oil in the lubricating system of a hydrocarbon engine, the combination with the engine having a plurality of cylinders and having an oil supply reservoir, of a relatively small oil well separate from the reservoir, means for conveying the oil which drains from the engine cylinders to said well, said means including grooves or gutters at the lower ends of the cylinders, a refining device, means for conveying the oil from the well to the refining device and means for returning the oil from the refining device to the reservoir.
6. A hydrocarbon engine having a refining device, a crank case constituting a reservoir for lubricating oil, an oil well of a relatively small capacity at the level of the crank case, means for conveying the oil which drains from the cylinders into said well, means for conveying the oil from said well to the refining device and means for returning the pure oil from the refining device to the reservoir in the crank case.

In testimony whereof I hereunto affix my signature.

JAMES A. WATSON.
